UNITED STATES PATENT OFFICE.

WILLIAM CLAASSEN, OF HOVEN, SOUTH DAKOTA.

LOCK.

Application filed October 29, 1923. Serial No. 671,506.

This invention relates to locks, and more particularly to door locks.

An object of the invention is to provide a lock of very simple construction employing no springs, which is positive in operation.

In the preferred form of the invention, I provide a slideable bolt having an opening therein, and a key adapted to extend through the door, having a depending end portion adapted to enter said opening.

In the accompanying drawings, I have shown one embodiment of the invention. In this showing:

Figure 1 is a front elevation of a portion of a door showing the key plate and showing the remaining portions of the lock in dotted lines,

Figure 2 is a rear elevation showing the lock in full lines,

Figure 3 is a vertical sectional view through a portion of a door, the key being shown in elevation in position for locking the door,

Figure 4 is a horizontal sectional view through the bolt showing the opening for the reception of the key, and,

Figure 5 is a perspective view of the bolt and guides or keepers.

Referring to the drawings, the reference numeral 1 designates a portion of a door adapted to be arranged in closed position adjacent a door casing 2. The lock forming the subject matter of the present invention consists of a plate 3, adapted to be arranged on the inside of a door and adapted to support suitable guides or keepers 4. The guides or keepers are secured to the plate and the door by means of rivets 5 or other suitable fastening elements. These guides are adapted to receive a slideable bolt 6, the end of which is adapted to be received behind the door casing, as shown in Figure 3 of the drawings, when in locked position, to prevent opening of the door. The lower face of the bolt is provided with an enlarged portion 7, adapted to engage the keepers to limit the movement of the bolt. The outer face of the bolt is provided with a depression or opening 8. A key hole 9 is arranged in the door above the bolt and a key hole plate 10 is secured to the front of the door. The key hole plate is provided with an opening adapted to be arranged in alignment with the opening 9 and the rear plate 3 is likewise provided with an opening in

alignment with the opening 9. A key 11 is adapted to be inserted through this opening. The inner end of the key is forked, and is adapted to receive a reduced portion 12 of a pivoted end member 13. This end member is secured to the forked end of the key by means of a pin 14. As shown, the reduced portion of the end member and the forked end of the key are provided with inclined faces 15, which are adapted to engage each other when the end member is in the dotted line position shown in Figure 3 of the drawings to prevent movement of the end member on its pivot. The lower end of the end member is provided with a finger 16, adapted to be received in the opening 8 in the bolt.

The operation of the device is as follows:

The key is inserted through the opening 9 with the finger 16 extending upwardly, as shown in dotted lines in Figure 3 of the drawings. The outer end of the end member 13 is heavier than the inner end and tends to swing the end member to a substantially vertical position. With the key in the inverted position shown in dotted lines in Figure 3 of the drawings, the inclined faces 15 limit the movement of the end member and retain it in a substantially horizontal position in alignment with the body portion 11 of the key. After the key has been passed through the opening 9, it is turned substantially 180 degrees and the heavier outer end of the end member then swings the end member to a substantially vertical position as shown in full lines in Figure 3 of the drawings. The finger 16 then enters the opening 8 and by revolving the key on its axis, the bolt may be locked or unlocked.

Attention is called to the fact that the distance from the key hole to the hole in the bolt must be the same as the distance between the pivot 15 and the finger 16 and the slightest variation will make it impossible to work the lock. This makes it possible to make practically any number of the locks apparently alike in external appearance, each of which must however, be operated by a different key.

It is to be understood that the form of my invention herewith shown and described is to be taken as a preferred example of the same, and that various changes in the shape, size, and arrangement of parts may be resorted to without departing from the spirit

of the invention or the scope of the subjoined claims.

I claim:

1. A lock comprising a bolt adapted to be slidably mounted on the inner face of a door, said bolt being provided with a recess in its outer face, and a key adapted to be passed through a key hole opening in the door out of alinement with the bolt, said key being provided with a pivoted end member adapted to assume an angular position with respect to the body of the key, a finger formed on the end of said end portion and adapted to enter said recess, and means for limiting the movement of said pivoted end portion in one direction.
2. A lock comprising a pair of keepers adapted to be arranged on the inner face of a door and spaced from each other, a bolt

slidably mounted in said keepers, said bolt being provided with an enlarged portion forming a pair of spaced shoulders adapted to engage the sides of said keepers to limit the movement of the bolt, said bolt being further provided with a recess in its outer face, and a key adapted to be passed through a key hole opening in the door out of alinement with the bolt, said key being provided with a pivoted end member capable of being retained in alinement with the body portion of the key when in one position and being adapted to assume an angular position by gravity when said key is rotated, and a finger formed on the end portion and adapted to enter said recess.

In testimony whereof, I affix my signature.

WILLIAM CLAASSEN.
